CASING FOR A HAND MANIPULABLE TRANSDUCER

Robert E. Burridge, Montclair, N.J., assignor to Litton Business Systems, Inc., Orange, N.J.

Filed Oct. 28, 1969, Ser. No. 19,774

Term of patent 14 years

Int. Cl. D14—99

U.S. Cl. D26—14

FIG. 1

FIG. 2

FIG. 3

FIG. 4

FIG. 5

FIG. 6

FIG. 7

FIG. 8

FIG. 9

FIG. 10

FIG. 1 is a side perspective view of a casing for a transducer or similar article;

FIG. 2 is a side elevational view thereof;

FIG. 3 is a rear elevational view thereof;

FIG. 4 is a top plan view thereof;

FIG. 5 is a bottom plan view thereof;

FIG. 6 is a perspective view of another embodiment of a casing for a transducer or similar article;

FIG. 7 is a side elevational view thereof;

FIG. 8 is a rear elevational view thereof;

FIG. 9 is a top plan view thereof; and

FIG. 10 is a bottom plan view thereof.

I claim:

The ornamental design for a casing of a hand manipulable transducer, as shown and described.
